UNITED STATES PATENT OFFICE.

REUBEN C. BAKER, OF COALINGA, CALIFORNIA.

SAFETY-CLUTCH FOR ELEVATORS.

1,203,300.

Specification of Letters Patent.

Patented Oct. 31, 1916.

Application filed August 28, 1915. Serial No. 47,859.

To all whom it may concern:

Be it known that I, REUBEN C. BAKER, a citizen of the United States, residing at Coalinga, in the county of Fresno and State 5 of California, have invented a new and useful Safety-Clutch for Elevators, of which the following is a specification.

This invention relates to a safety clutch for use in connection with elevators, one of 10 the objects of the invention being to provide a means whereby in the event of the breakage of the hoisting cable of an elevator, gripping members will be automatically thrust into engagement with guide rails at 15 the sides of the path of the car or cage, and will grip said rails tightly, the pressure increasing in proportion to the weight to which the members are subjected, so that there is no possibility of the car falling in the event 20 of such breakage.

A further object is to provide means whereby each clutch is thrown positively into engagement with the guide rail.

With the foregoing and other objects in 25 view which will appear as the description proceeds, the invention resides in the combination and arrangement of parts and in the details of construction hereinafter described and claimed, it being understood 30 that changes in the precise embodiment of the invention herein disclosed, can be made within the scope of what is claimed, without departing from the spirit of the invention.

35 In the accompanying drawings the preferred form of the invention has been shown.

In said drawings:—Figure 1 is a view partly in elevation and partly in section of 40 the upper portion of an elevator cage and showing the parts constituting the present invention in position thereon. Fig. 2 is a section on line A—B Fig. 1. Fig. 3 is an enlarged section on line C—D Fig. 1.

45 Referring to the figures by characters of reference 1 designates a portion of an elevator cage and 2 designates guide rails at opposite sides of the cage. Mounted on the top of the cage and adjacent each of the 50 guide rails are opposed upwardly converging deflecting strips 2' fastened to the cage in any suitable manner and secured together at their upper ends, as shown for example at 3. Interposed between each pair of deflecting strips 2' are opposed clutch mem-

bers or shoes 4 the outer faces of which are recessed, as at 5 so as to straddle the rails 2, as shown. The inner or adjoining faces of the clutch members or shoes 4 are preferably parallel and toothed, while the outer faces are inclined and parallel with the deflecting strips 2'. Secured to the members or shoes 4 are holding plates 6 which loosely engage the outer sides of the strips 2' as shown in Fig. 2, thus to hold the shoes or 60 clutch members 4 loosely against the inner sides of the strips 2'. The inner plates 6 upon each pair of shoes or clutch members 4 are pivotally connected to the outer end of a lever 7 fulcrumed as at 8 upon the top 65 of the cage. The two levers 7 are extended toward each other and are pivotally connected at their inner ends, as shown at 9, these ends being also connected to a bolt 10 extending upwardly therefrom and secured 70 to the hoisting cable 11. A bracket 12 is secured upon the cage 1 and constitutes a guide for the bolt 10 and also an abutment for a spring 13 which is coiled about the bolt 10 and bears downwardly against a 75 collar 14 secured to the bolt. This spring may be housed in a casing 15 if desired.

It will be obvious that as long as the cage is being supported by the cable 11, the spring 13 will be held under compression between 80 the collar 14 and the bracket or abutment 15, and the shoes 4 will be pressed downwardly against the top of the cage thus to be held out of contact with the rails 2. If, however, the cable 11 should break, the 85 springs 13 will promptly expand, thereby thrusting downwardly against the collar 14 and actuating the two levers 7. These levers will thrust upwardly upon the plates 6 and cause the shoes or clutch members 4 to ride 90 upwardly along the inner faces of the strips 2'. These deflecting strips 2' will cause the shoes to become wedged between them and the rails 2 with the result that the frictional engagement between the rails and the shoes 95 will be sufficient to support the cage and prevent it from descending. Obviously the greater the weight of the cage the more firmly will be the gripping action by the 100 shoes 4 upon the rails 2.

Importance is attached to the fact that the apparatus constituting the present invention can be applied readily to cages already in use and does not ordinarily require the use of any particular kind of 110

guide rail, the shoes 4 being readily arranged to engage any kind of guide rail at the sides of the cage.

What is claimed is:—

- 5 The combination with an elevator cage and guide rails, opposed upwardly converging deflecting strips secured upon the cage at each side thereof, opposed clutch members between the strips of each pair, said
- 10 clutch members having their active faces recessed to straddle a guide rail, holding devices secured to each of the clutch members and slidably engaging the outer sides of the deflecting strips, a pivot device connecting
- 15 certain of the holding devices upon the

clutch members of each pair, oppositely extending levers fulcrumed upon the cage and connected, at their outer ends, to the respective pivot devices, a hoisting cable connected to the inner ends of the levers, and means 20 for moving said inner ends downwardly automatically should the cable break.

In testimony that I claim the foregoing as my own, I have hereto affixed my signature in the presence of two witnesses.

REUBEN C. BAKER
